J. M. BLONDELL.
RAILWAY CAR GEAR.

No. 449,643.

Patented Mar. 31, 1891.

UNITED STATES PATENT OFFICE.

JOHN M. BLONDELL, OF BALTIMORE, MARYLAND, ASSIGNOR TO FREDERICK E. TOBE, OF SAME PLACE.

RAILWAY-CAR GEAR.

SPECIFICATION forming part of Letters Patent No. 449,643, dated March 31, 1891.

Application filed August 7, 1890. Serial No. 361,877. (No model.)

To all whom it may concern:

Be it known that I, JOHN M. BLONDELL, a citizen of the United States, residing at Baltimore, and State of Maryland, have invented 5 certain new and useful Improvements in Railway-Car Gear; and I do hereby declare the following to be a full, clear, and exact description of the invention, such as will enable others skilled in the art to which it appertains 10 to make and use the same.

My invention relates to what is known in the trade as "railway-car gear"—that is to say, that portion of the running-gear of a street-railway-car vehicle comprising the axle 15 journal-box, the carrying-springs, the pedestal stay-brace, and the posts for securing the axle to the body of the car; and my improvement consists of certain novel parts and combination of parts, the separate features of which 20 will be separately and specifically pointed out in the claims concluding this specification, in connection with the accompanying drawings, in which—

Figure 1 represents a side elevation of a 25 railway-car gear embracing my invention. Fig. 2 is a vertical longitudinal section of the same. Fig. 3 is a vertical cross-section of the same, taken on the line *a a* of Fig. 2. Fig. 4 is a horizontal section taken on the line *b b* 30 of Fig. 2. Fig. 5 shows one of the separate guide-irons for the journal-box guide-posts of the gear; and Fig. 6 shows the inside face of the axle-box lid to expose its removable plate, which receives the end-thrust of the axle.

The object of my invention is to produce a 35 car-gear having separate wearing parts which are adapted for adjustment to present new wearing-surfaces at the wearing-points, to reverse their relative positions to their wearing 40 portions, and to remove and renew them when necessary, and all this at very little cost in time, labor, and material.

My invention gives the important advantage of removing the old gear as an entirety 45 from the body of the car and of quickly replacing it by a repaired or new one, which advantage cannot be obtained in gear constructed with posts running through the sill of the car.

50 *a* shows a portion of the pedestal stay-brace,

which is secured to the car-sill in the usual manner.

b is the pedestal, and *b'* is the metal sill-plate, which has a vertical flange *b²* covering the outer face of the car-sill, and is secured 55 by bolts passing up through the plate, and also by bolts through its flange. At its under side this plate has screw-threaded bosses *c*, into which are screwed the posts *d*, the lower ends of which pass through the pedestal stay- 60 brace and are secured thereto by nuts *e* at the under side of said stay-brace.

f is the journal-box, which, with its pedestal, is supported upon the stay-brace and secured 65 to the car by four posts.

g are the carrying-springs mounted upon the pedestal by the posts on each side of the journal-box *d*, and *h* is a supplemental spring upon the journal-box, of less height than the carrying-springs, to receive the greatest load 70 of the car.

The vertical movement of the car-body upon its springs causes the posts to move through the pedestal, and these posts, as I have provided, take the place of the usual pedestal- 75 rods, which pass up through the car-sill and permit the car-gear to be constructed as an entirety, with its posts independent of any connection with the car-body. As a means of preventing the wear of these pedestal-posts 80 and the wear of the sides of the journal-box, I provide a removable wear part for each. For the box guide-posts such wearing part is a cylindrical sleeve *i*, abutting upon and be- 85 tween the stay-brace and the sill-plate bosses, and for the journal-box such wearing part is a separate guide-iron *j*, having a concave wear-face conforming to the convex surface 90 of the guide-sleeve, as seen in Figs. 4 and 5. This guide-iron is preferably held in place 95 against the side of the journal-box by ribs *k*, so that it can be lifted out and a new one inserted. These guide-posts have heretofore been used bearing directly upon the axle-box, and both the posts and the box were rendered 95 useless by such wear. This guide-iron is also preferably made wedge-shaped, so as to be slipped down into its seat between the box-ribs.

The pedestals are formed with seats *l* for the rubber cushions *m*, which are provided 100

with metal-sleeved seats *n* for the springs, while a metal cap *o* forms a seat for the upper end of the spring and a seat for the upper rubber cushion *p*, which is placed against the under-side of the sill-plate. To protect the posts of these springs from wear by contact with the metal seats of the springs, I provide the said posts with cylindrical sleeves *q*, which, like the guide-sleeves for the journal-box and post, abut upon and between the screw-threaded bosses of the sill-plate and the stay-brace. These wear-sleeves of all the posts can be turned or rotated to present a new wearing-surface, and they can be turned end for end to change the location of the wearing-surface, and they can be readily and cheaply removed and replaced by new sleeves when desired, and thus avoid the expense and trouble of replacing the posts themselves. These sleeves form auxiliary posts and re-enforce and strengthen the posts proper, and these sleeves form additional shoulder-bearings to these posts, and serve to strengthen, stiffen, and keep the gear in firm condition, and thereby lessen the rocking movement of the parts in the direction of the thrust of the car and their consequent loosening.

The axle-box lid *r* is provided with a removable bearing-plate *s* at its inner side to receive the end-thrust of the axle *t*, and I make this plate of brass or other suitable bearing metal and seat it in the lid by ribs to permit its renewal when worn. I provide the stay-brace with an abutment *u*, against which that end of the gear abuts which is opposite to the direction of the draft for the purpose of receiving and sustaining the thrust of the axle-box against the gear in line with the draft, and thereby prevent the tilting and driving back of the gear.

While I prefer to use the removable wear-plates at the sides of the journal-box, yet it is obvious that the guide-posts with renewable wear-sleeves may be used in direct wear-contact with the box. It is also obvious that the box wear-plates may be used with the posts without the wear-sleeves.

I claim as my improvement—

1. In combination, in a railway-car gear, the axle-box, the posts *d*, the sleeves *i*, the pedestal-sill, stay-brace plates *b' a*, and the carrying-springs, the said posts having screw-threaded shouldered ends supporting said plates and the said sleeves forming the guide and wear bearings for the box, as shown and described.

2. In a railway-car gear, the combination, with the axle-box and the pedestal, of the box guide-posts, their wear-sleeves, and the wear-plates removably secured to said box.

3. In a railway-car gear, the combination, with the axle-box and the pedestal, of the box guide-posts and the box removable wear-plates.

4. In a railway-car gear, the combination, with the axle-box, the pedestal, and its posts, of the stay-brace having an abutment for the pedestal.

5. In a railway-car gear, the axle-box having its lid formed with dovetail guide-ribs on its inner side, in combination with a bearing-plate secured within said guide-ribs and the axle, as shown and described.

In testimony whereof I affix my signature in presence of two witnesses.

JOHN M. BLONDELL.
